H. G. SAAL

DIAPHRAGM STRUCTURE

Filed March 20, 1925

UNITED STATES PATENT OFFICE.

HENRY G. SAAL, OF CHICAGO, ILLINOIS.

DIAPHRAGM STRUCTURE.

Application filed March 20, 1925. Serial No. 17,080.

To all whom it may concern:

Be it known that I, HENRY G. SAAL, a citizen of the United States, residing at Chicago, in the county of Cook and the State of Illinois, have invented a certain new and useful Improvement in Diaphragm Structures, of which the following is a full, clear, concise, and exact description.

My invention relates to instrumentalities employing diaphragms, such as telephones, and has for its object the provision of means whereby the diaphragms may be clamped in place by rotatable clamping members that are enabled to perform their function without imparting any distorting turning effort to the diaphragms. In carrying out my invention a nonrotating guard is interposed between the diaphragm and rotatable clamping member, this guard preventing said clamping member from exerting material turning effort upon the diaphragm which is thus guarded from distortion.

The invention will be more fully explained in connection with the accompanying drawing showing the preferred embodiment thereof as applied to telephone receivers. In the drawing Fig. 1 is a longitudinal sectional view of such a telephone receiver taken on line 1—1 of Fig. 2, with parts shown in elevation and parts broken away; Fig. 2 is a sectional view on line 2—2 of Fig. 1; Fig. 3 is a sectional view on line 3—3 of Fig. 2; Fig. 4 is a sectional view on line 4—4 of Fig. 2; and Fig. 5 is a perspective view showing a diaphragm supporting cup and a guard ring in separated relation.

Like parts are indicated by a similar characters of reference throughout the different figures.

The circular diaphragm 1 may be of any suitable sheet material such as mica or steel. A cup 2 carries the peripheral portion of the diaphragm upon its rim. A casing is shown which comprises a body member 3, made of gutta percha, and a rotatable cap 4, of similar or suitable material threaded upon the body member, the rim portions of said diaphragm and cup being interposed between the body member and cap of the casing. A guard ring 5 is interposed between the cap and the peripheral portion of the diaphragm, said cap having an annular ridge 6 engaging said ring which is coaxial with the ridge and cup rim. The rim por-

tions of said cup and ring have engaging groove and tongue holding formation 7 and 8 to prevent the ring from turning materially as the cap is turned.

The casing body 3 and the cup 2 jointly 60 constitute a support for the diaphragm.

Where the invention is embodied in a telephone receiver, the cup may carry the magnet system 9 which is in actuating relation with the diaphragm, as through a 65 stylus 10 which connects the diaphragm and the armature 11 of the electromagnet 9' of the magnet system.

It is obvious that changes may be made without departing from the spirit of my 70 invention.

Having thus described my invention I claim as new and desire to secure by Letters Patent the following:—

1. The combination with a diaphragm 75 support; of a rotatable clamping member in threaded connection with said support; a diaphragm interposed between said support and clamping member; and a guard clamped between said clamping member and 80 diaphragm and held from rotation by said support.

2. The combination with a support having an annular diaphragm seat; of a rotatable clamping member in threaded connection with said support and having an annular ridge facing and substantially coaxial with said diaphragm seat; a circular diaphragm whose edge portion is interposed between said seat and ridge; and a guard 90 ring clamped between and substantially coaxial with said seat and ridge and held from rotation by said support.

3. The combination with a circular diaphragm; of a cup upon whose rim the 95 peripheral portion of the diaphragm is seated; a casing comprising a body member and a rotatable cap threaded upon the body member, the rim portions of said diaphragm and cup being interposed between the body 100 member and cap of said casing; and a guard ring interposed between the cap and the peripheral portion of the diaphragm, said cap having an annular ridge engaging said ring, the rim portions of said cup and ring 105 having engaging holding formations to prevent the ring from turning materially as the cap is turned.

4. The combination with a circular diaphragm; of a cup upon whose rim the 110

- 5 peripheral portion of the diaphragm is seated; a casing comprising a body member and a rotatable cap threaded upon the body member, the rim portions of said dia-
10 phragm and cup being interposed between the body member and cap of said casing; and a guard ring interposed between the cap and the peripheral portion of the dia-
15 phragm; said cap having an annular ridge engaging said ring, the rim portions of said cup and ring having engaging groove and tongue holding formations to prevent the ring from turning materially as the cap is turned.
20 5. The combination with a circular dia-
25 phragm; of a cup upon whose rim the peripheral portion of the diaphragm is seated; a casing comprising a body member and a rotatable cap threaded upon the body member, the rim portion of said diaphragm and cup being interposed between the body member and cap of said casing; and a guard ring interposed between the cap and the peripheral portion of the diaphragm, said
30 25 cap having an annular ridge engaging said
35 ring, the rim portions of said cup and ring having engaging groove and tongue holding formations to prevent the ring from turning materially as the cap is turned.
40 6. The combination with a diaphragm support; of a rotatable clamping member in threaded connection with said support; a diaphragm interposed between said support and clamping member; and a guard clamped between said clamping member and
45 diaphragm and held from rotation.
7. The combination with a support having an annular diaphragm seat; of a rotatable clamping member in threaded connection with said support and having an annular ridge facing and substantially coaxial with said diaphragm seat; a circular diaphragm whose edge portion is interposed between said seat and ridge; and a guard ring clamped between and substantially coaxial with said seat and ridge and held from rotation.

In witness whereof, I hereunto subscribe my name.

HENRY G. SAAL.
